CLAIM

The ornamental design for a battery pack, as shown and described.

DESCRIPTION

FIG. 1 is a top front perspective view of the battery pack of our new design;

FIG. 2 is a top plan view of the battery pack of FIG. 1;

FIG. 3 is a left side elevation view of the battery pack of FIG. 1;

FIG. 4 is a right side elevation view of the battery pack of FIG. 1;

FIG. 5 is a bottom plan view of the battery pack of FIG. 1;

FIG. 6 is a rear elevation view of the battery pack of FIG. 1;

FIG. 7 is a front elevation view of the battery pack of FIG. 1; and,

FIG. 8 is a rear top perspective view of the battery pack of FIG. 1.

The broken lines depict portions of the battery pack that form no part of the claimed design.
